UNITED STATES PATENT OFFICE.

MAXIME BIETTE, OF NANTES, FRANCE, ASSIGNOR TO BIETTE, INC., OF NEW YORK, N. Y., A CORPORATION OF NEW YORK.

DESIGN FOR A DISPLAY BOX FOR SOAPS.

Application filed February 9, 1926. Serial No. 16,465. Term of patent 7 years.

To all whom it may concern:

Be it known that I, MAXIME BIETTE, a citizen of the Republic of France, residing in the city of Nantes, France, have invented a new, original and ornamental Design for Display Box for Soaps, of which the following is a specification, reference being had to the accompanying drawing, forming a part thereof.

In the drawing

I claim:

The ornamental design for a display box for soaps substantially as shown.

MAXIME BIETTE.
